The ornamental design for a cutting machine for railroad rail, as shown and described.

DESCRIPTION

FIG. 1 is a left side perspective view of a cutting machine for railroad rail showing my design;

FIG. 2 is a right side perspective view thereof;

FIG. 3 is a right side elevational view thereof;

FIG. 4 is a left side elevational view thereof;

FIG. 5 is a front elevational view thereof;

FIG. 6 is a rear elevational view thereof; and,

FIG. 7 is a top plan view thereof.

The cutting disk shown in FIG. 2 has been omitted from the balance of the drawing figures for ease and clarity of illustration.

FIG. 1

FIG. 2

FIG. 3

FIG. 4

FIG. 5

FIG. 6

FIG. 7
